SKYLIGHTS

Robert A. Boyd, Ann Arbor, Mich., assignor to Owens-Illinois Glass Company, a corporation of Ohio

Application May 29, 1953, Serial No. 358,277

8 Claims. (Cl. 88—59)

This invention relates to the utilization of daylight for lighting the interior of buildings through an opening in a roof or ceiling.

A major problem in the utilization of daylight through an opening in a roof or ceiling is that the direct sunlight from high altitudes provides an excessive amount of light and heat. This condition is especially present during the summer months when the sun is at the higher altitudes. A proposed solution to this problem is shown in my pending application titled Skylights, Ser. No. 295,730, and filed June 26, 1952.

It is an object of this invention to provide an improved skylight which rejects direct sunlight from high altitudes and transmits sunlight from low altitudes and light from the northern sky.

Other objects of the invention will appear hereinafter.

Basically my invention comprises controlling the transmission of daylight through an opening in a roof or ceiling by interposing four interfaces, such as are present in a hollow glass block or in two spaced sheets of glass, in the opening. In such a structure the interfaces are conventionally termed Faces 1, 2, 3, and 4—Face 1 being the interface nearest the light, Faces 2 and 3 being the intermediate interfaces and Face 4 being the interface nearest the interior of the room. According to my invention, Face 2 is provided with a series of parallel prism-shaped ribs extending in a generally east-west direction. Face 1 may be provided with a smooth surface or a series of longitudinal ribs extending in a generally north-south direction. Faces 3 and 4 are provided with ribs and/or prisms or are opalescent in order to diffuse the transmitted light into the interior being lighted.

The prism shaped ribs on Face 2 are so constructed and arranged that direct sunlight at high altitudes is rejected whereas sunlight from the low altitudes and light from the northern sky are transmitted.

Referring to the accompanying drawings:

Fig. 1 is a diagrammatic representation of the results obtained by a skylight utilizing my invention;

Fig. 2 is a cross-sectional elevational view of a room showing the excessive sunlight from the sun at higher altitudes;

Fig. 3 is a sectional view of a hollow block incorporating my invention;

Fig. 4 is a cross-sectional view of a skylight comprising two sheets of glass and incorporating my invention;

Fig. 5 is a fragmentary cross-sectional view of Faces 1 and 2 on a greatly enlarged scale showing the path of light rays from high altitude angles;

Fig. 6 is a fragmentary cross-sectional view of Faces 1 and 2 on a greatly enlarged scale showing the path of light rays from various angles;

Fig. 7 is a cross-sectional view on a greatly enlarged scale of a modified form of Face 2, showing the path of light rays from various angles in the sky;

Fig. 8 is a series of curves of great circle transmission obtained by testing several forms of the invention;

The problem of illumination through an opening in a ceiling or roof may be illustrated by referring to a typical room. As shown in Fig. 2, sunlight passing through opening 20 in ceiling 21, emanates from a southerly direction in the Northern hemisphere. At high altitude angles of the sun the amount of light and heat emanating therefrom is excessive and undesirable. This is shown more clearly by the following table of meteorological data representing conditions at 42° North latitude:

Table I

Day of Year	Maximum Sun Altitude, degrees	Normal Sun Intensity (ft.-c.)	Horizontal Surface Illumination	
			Sun Only (ft.-c.)	Clear Sky (ft.-c.)
30 June 21	71 $\frac{1}{2}$	9,180	8,700	1,600
May 21 and July 21	68 $\frac{1}{2}$	9,070	8,400	1,500
Apr. 21 and Aug. 21	60	8,900	7,700	1,400
Mar. 21 and Sept. 21	48 $\frac{1}{2}$	8,800	6,600	1,200
Feb. 21 and Oct. 21	37 $\frac{1}{2}$	8,250	5,000	1,000
Jan. 21 and Nov. 21	28	7,500	3,500	800
Dec. 21	24 $\frac{1}{2}$	7,000	2,900	800

As shown in Table I, the sun altitude and sun intensity vary throughout the year, the maximum occurring during the months from April through August. Table I further indicates that the greater portion of the horizontal surface illumination is due to light from the sun and a much lesser portion is due to the clear (northern) sky.

I have found that the desired control of illumination through an opening may be obtained by interposing four glass interfaces between the light source, namely the sun and sky, and the interior, certain interfaces having prism shaped ribs thereon of particular configuration, as hereinafter described.

As shown in Figs. 3 and 4, the four interfaces may be found in a glass block 24 or in two spaced sheets of glass, 25, 26. In such structures the interfaces are conventionally referred to as Faces 1, 2, 3, and 4—Face 1 being the interface nearest the light, Faces 2 and 3 being the intermediate interfaces and Face 4 being the interface nearest the interior of the room.

Face 1 is provided with a smooth surface 27 or a series of transverse ribs. Face 2 is provided with a series of parallel prism shaped ribs 28, hereafter referred to as prisms, having particular configurations and extending longitudinally in a generally east-west direction when the skylight is placed in an opening in a ceiling or roof. Faces 3 and 4 may be provided with ribs or prisms, 29, 30 as hereinafter described such that daylight transmitted thereto is diffused into the interior of the room.

As shown diagrammatically in Fig. 1, a skylight incorporating my invention rejects sunlight from high altitude angles (zone II) and transmits sunlight from low altitude angles and light from the northern sky (zones I, III).

According to my invention, sunlight from high altitude angles is refracted by Face 1 and totally internally reflected at Face 2 and thereby rejected. More specifically as shown in Fig. 5 the prisms 28 on Face 2 have surfaces 31, 32 at an included angle P. When the skylight is placed

in an opening in a ceiling or roof the prisms 28 extend in a generally east-west direction, the northern slope or surface 32 facing a southerly direction.

A light ray L_1 at sun altitude angle a_1 is refracted at Face 1, transmitted to and reflected from the surface 31 to surface 32, refracted through surface 32 to surface 31 of the adjacent prism, refracted through surface 31 to surface 32 and reflected therefrom to Face 1 and refracted out to the atmosphere. In a similar manner, light rays at angle a , striking the northern slope or surface 32 are totally rejected. This is represented on Fig. 5 by the double arrows.

The incorporation of the prism structure shown in Fig. 5 in a skylight construction may be more clearly represented by referring to Fig. 6. It may be observed that a ray of sunlight L_2 from a low altitude a_2 is refracted at Face 1, and refracted out of surface 32. A light ray L_3 , representing light from the northern sky at an angle a_3 is refracted at Face 1 at the surface 31 toward the interior.

As shown in Fig. 6 the construction of the prisms on Face 2 rejects the sunlight from the high altitude angles and permits sunlight from the low altitude angles and light from the northern sky to be transmitted toward the interior. By utilizing two prisms to totally reject the sunlight from high altitude angles, I have found that a broad range of rejection of high altitude angles is obtained.

I have found that the angle P between surfaces of the prism is preferably 75° . I have also found that for a latitude of 42° N. the angle b , which the surface 31 forms with the plane of the glass is preferably 40° . After constructing the skylight in accordance with my invention with the angle $P=75^\circ$ and the $b=40^\circ$, and conducting illumination tests thereon the curve of great circle illumination, shown as a solid line A in Fig. 8, is obtained. This curve represents the percent of light transmitted at various sun altitudes for the construction, the prisms extending in an east-west direction.

As shown in the curve in Fig. 8, there is an area or zone ranging between 52° and 71° of sun altitude at which maximum rejection of direct sunlight is obtained. It may be noted that the zone may extend between 48° and 79° , namely for approximately 31° , with substantial rejection of sunlight. Referring to Table I, which shows sun altitudes for 42° N. latitude, it may be observed that this zone of 31° is sufficiently broad to reject sunlight from high sun altitudes from March through September, namely, $71\frac{1}{2}^\circ - 48\frac{1}{2}^\circ = 23^\circ$.

It is apparent therefore that by utilizing a prismatic structure which rejects sunlight by total rejection through two prisms, I have been able to provide a broad area or zone of rejection of sun altitudes. At the same time sunlight from the lower sun altitudes and light from the northern sky is permitted to pass through to the interior being lighted.

A modification of the prisms on Face 2 is shown in Fig. 7. In this form the surfaces 33, 34 of the prism have been changed in slope, without affecting the included angle P , thus shifting or rotating the position of the prism about its longitudinal or east-west axis. The surface 33 forms an angle b , with the plane of the glass, the angle b , being greater than the angle b , in the form of the invention shown in Fig. 6. By such a construction a light ray L_1 at an altitude angle a , is reflected and totally internally reflected through two prisms and finally rejected to the atmosphere. In a similar manner a light ray striking the northern slope, surface 34, from an altitude angle a , is rejected. This latter condition is shown by the double arrows. Light rays L_2 , L_3 from low sun altitude angles and from the northern sky, respectively, are subjected to substantially the same action as in the other form of the invention shown in Fig. 6.

Contrasting the construction in Fig. 7 with that in Fig. 6, it is found that a_1 is greater than a_1 . This indicates that by increasing the angle b , which one surface, the southerly slope, of the prism makes with a horizontal plane,

the area or zone of rejection of light rays from high sun altitude angles may be changed and shifted to include higher altitude angles. If the construction shown in Fig. 7 were made, for example, with the angle b_2 equal to 45° , the curve of great circle transmission would be that in curve B of Fig. 8. It may be seen that the zone of rejection is approximately the same as in the form of the invention shown in Fig. 6, and represented by a curve A, but has been shifted to the right so that the zone now extends from approximately 59° to 90° . Referring to standard tables of sun altitudes it may be determined that this prism structure would be satisfactory for a latitude of 30° N. wherein the maximum sun altitude is $83^\circ+$.

In a similar manner, by decreasing the angle b the area or zone of rejection may be changed or shifted to include lower altitude angles. For example, if b is made equal to 35° the curve of great circle transmission designated as curve C in Fig. 8 is obtained, rejecting sun altitude from 33° to 64° . A reference to the table of sun altitudes indicates that the structures represented by this curve would be adequate to reject sunlight at latitudes of 48° N. wherein the maximum sun altitude is $65^\circ+$.

I have also found that the zone of rejection may be broadened even further by increasing the included angle P between the surfaces of the prisms on Face 2. Although maximum rejection will be obtained when P equals 75° , I have found that substantial rejection will take place when P is varied between 60° and 87° . It should be observed that when the angle P is changed the range of sun altitudes partially rejected is increased but the range of sun altitudes totally rejected is proportionately decreased.

I have also found that in conjunction with the prismatic structure on Face 2 a glass fiber diffusing mat 35 may be used between the spaced sheets of glass, as shown in Fig. 9. Moreover, a diffusing structure should be used on Faces 3 and 4 in order that the light which is transmitted through Faces 1 and 2 will be diffused into the interior. The diffusing structure preferably comprises a multiplicity of depressed pyramids 36, 37 on Faces 3 and 4, respectively. As shown in Figs. 10 and 12, the pyramids preferably extend in rows at angles to each other on the respective Faces 3 and 4. The pyramids 36 on Face 3 extend diagonally across the face while the pyramids 37 on Face 4 extend in rows parallel to the sides of the face. In addition, the pyramids on Face 3 have concave surfaces 38 whereas the pyramids on Face 4 have convex surfaces 39.

By the above structure of the pyramid on Faces 3 and 4, I have found that a diffusion of the transmitted light is obtained in a circular manner as contrasted to the non-circular configuration that would be obtained if a diffusing structure utilizing parallel ribs were used.

Fig. 14 shows a modified form of pyramids on Face 3 which is intended to aid in bringing rays of sunlight which tend to continue to travel in a northerly direction into a more nearly vertical direction toward the interior. In this structure, the pyramids 40 on Face 3 are made unsymmetrical by displacing the apex 41 of the depressed pyramid toward one side of the block in such a manner that the apex will be displaced toward the north when the sky light is placed in position in a vertical opening. I have found that this structure tends to cause any light rays which strike Face 3 in a direction which is not normal to be corrected toward the normal. Surfaces 42 are concave.

Although best results are obtained in my skylight structure by positioning the skylight in such a manner that the prisms extend in an east-west direction, substantially the same results will be obtained if the prisms extend in a generally east-west direction and not in a precise east-west direction.

It should, of course, be understood that in practice a slight slope will be given to the skylight for drainage purposes equal on the average to $1/4$ per foot, the slope being to the north, east, or west but not to the south.

The specific angles in this application are for a glass having an index of refraction of 1.52. However, it is also within the scope of my invention that light transmitting materials other than glass may be used embodying the teachings of my invention, with such modifications that might be necessary and apparent to those skilled in the art.

Modifications may be resorted to within the spirit and scope of the appended claims.

I claim:

1. The combination of a ceiling having an opening therethrough, and a skylight interposed in said opening and comprising a series of four air-glass interfaces interposed in a horizontal position between the daylight and the interior being lighted, the second interface from the light source having a series of parallel unsymmetrical prisms formed thereon extending in a generally east-west direction, each said prism having surfaces forming an included angle of approximately seventy-five degrees, one said surface of each prism forming an angle of approximately forty degrees with a horizontal plane, said forty degree surface extending upwardly in a southerly direction such that sunlight from high altitude angles is totally rejected by total internal reflection within a pair of prisms and sunlight from low altitude angles and light from the northern sky are transmitted by refraction through the prisms toward the interior being lighted, said third and fourth interfaces having light diffusing means formed thereon for diffusing the light passing therethrough into the interior.

2. The combination of a ceiling having an opening therethrough and a skylight interposed in said opening and comprising a series of four air-glass interfaces interposed in a horizontal position between the daylight and the interior being lighted, the second interface from the light source having a series of parallel unsymmetrical prisms formed thereon extending in a generally east-west direction, each said prism having surfaces forming an inclined angle ranging from 60 to 87 degrees, one said surface of each prism forming an angle of approximately 40 degrees with a horizontal plane, said 40 degree surface extending upwardly in a southerly direction such that sunlight from high altitude angles is totally rejected by total internal reflection within a pair of prisms and sunlight from low altitude angles and light from the northern sky are transmitted by refraction through the prisms toward the interior being lighted, said third and fourth interfaces having light diffusing means formed thereon for diffusing the light passing therethrough into the interior.

3. In a structure for controlling daylight, the combination comprising a ceiling having an opening therethrough

and a skylight interposed in said opening and comprising at least one sheet of light-transmitting material interposed in a generally horizontal position between the daylight and the interior being lighted, said sheet having a series of unsymmetrical parallel prisms on the face thereof nearest the interior, the axes of said prisms extending in a generally east-west direction, each said prism having a first surface extending upwardly in a southerly direction and a second surface extending upwardly in a northerly direction.

10 5 The combination of a ceiling having an opening therethrough, and a skylight interposed in said opening and comprising a series of four air-glass interfaces interposed in a horizontal position between the daylight and the interior being lighted, the second interface from the light source having a series of parallel unsymmetrical prisms formed thereon extending in a generally east-west direction, each said prism having surfaces forming an included angle of approximately seventy-five degrees, one said surface of each prism forming an angle of approximately forty degrees with a horizontal plane than the angle which said first surface forms with a horizontal plane, said angles which said surfaces form with a horizontal plane, and the included angle between said surfaces ranging from 60 to 87° such that sunlight from high altitude angles is totally rejected by total internal reflection within a plurality of said prisms and sunlight from low altitude angles and light from the northern sky are transmitted by refraction through the prisms toward the interior being lighted.

15 10 20 The combination set forth in claim 3 wherein the included angle between said first and second surfaces of each said prism is approximately 75°, the angle which said first surface forms with the horizontal plane being approximately 40°, and the angle which said second surface forms with a horizontal plane being approximately 65°.

25 15 20 25 The combination set forth in claim 3, the angle which said first surface forms with a horizontal plane being approximately 40°.

30 25 30 The combination set forth in claim 3 wherein said sheet of light-transmitting material comprises one of the walls of a glass block.

35 30 35 35 The combination set forth in claim 6 including a mat of diffusing material interposed in parallel spaced relationship between said sheets of light-transmitting material.

8. The combination set forth in claim 7 wherein said mat comprises glass fibers.
